UNITED STATES PATENT OFFICE.

WILLIAM C. FOSTER, OF PROVIDENCE, RHODE ISLAND, ASSIGNOR TO THEODORE W. FOSTER & BROTHER COMPANY, OF PROVIDENCE, RHODE ISLAND.

BELT BUCKLE.

Application filed June 18, 1928. Serial No. 286,220.

This invention relates to belt buckles and the primary object thereof is to provide a buckle of the pivoted tongue type, wherein the tongue is concealed thereby enabling the 5 entire front of the buckle to be available for purpose of ornamentation.

A further object of the invention is to provide a buckle wherein the front thereof is mounted so as to be capable of being moved to 10 render the tongue accessible for purpose of adjustment or removal of the belt, and which upon such movement automatically effects outward or releasing movement of the buckle tongue, thus facilitating removal of the belt.

15 In the drawings:—

Figure 1 is a front elevation of the invention in operative position;

Figure 2 is a section on line 2—2 of Fig. 1;

Figure 3 is a front elevation of the invention in detached position and showing the parts open; and

Figures 4 and 5, are sections on lines 4—4 and 5—5 respectively of Figure 3.

In proceeding in accordance with the present invention a back member or main frame 1, is employed which has flanged sides 2, an end bar 3, and a connecting strip 4, which latter is flanged at 5, and formed with a cutout 6, to receive the free end of a tongue 7. It will thus be noted that the strip 4, and its flange 5, form a partial housing for the free end of the tongue.

As depicted in Figures 4 and 5 of the drawings, the end bar 3, is preferably formed by rolling the metal in order to afford larger bearings for the tongue, where same is pivoted to the bar, the hinging or pivoting of the tongue being effected by cutting away the bar and by forming a hook 9 on the tongue 40 which latter engages about the bar and in the cutout.

A front plate 10, is hinged at 11, to the back member 1 and has flanged sides 12, which latter are formed to snap into or have frictional engagement with the sides 2, of the back member.

In operation, it will be observed that, due to the front plate or cover being hinged to the back at the end thereof opposite to the 50 end to which the tongue is pivoted, and due to the frictional latching of the cover plate in position upon the user pulling outwardly upon the free end A of the belt, the cover

will be moved about its hinge 11, and simultaneously, the tongue will be moved outwardly, thus facilitating removal of the belt. As depicted in Figure 2, of the drawings, the end A of the belt passes over strip 4 through the back 1, and under bar 3 while the opposite end B of the belt is looped about the end bar 60 3, and is secured by a snap fastener C.

It will also be noted that the front plate entirely conceals the tongue and also the back and further functions to hold the free end of the belt in position.

Having thus described my invention what I claim as new and desire to secure by Letters Patent is:—

1. In a belt buckle, a back having an end bar and a cross strip spaced therefrom and provided with an inturned flange on its inner side, the flange being formed with a cutout, a tongue hinged to the end bar, and a front plate hinged to the back at the end thereof opposite to said end bar, the back and front plate being formed with flanges formed to snap into engagement with one another so as to frictionally latch the front plate in position, the front plate extending over the tongue and back plate and concealing said parts.

2. In a belt buckle, a back, a tongue pivoted to the back and having a free end, a member connected to the back and engageable at its rear with the free end of the belt, and having a part formed with a cut-out to receive the free end of the tongue so as to form a seat for the free end of the tongue and to dispose the latter to lie closely adjacent to the inner face of the member, a front plate hinged at one end to the back at a point adjacent to said member and engageable with the free end of the tongue to hold same in its seat, the opposite end of the front plate at its rear being engageable with the free end of the belt whereby upon outward swinging of the free end of the belt same will swing the front plate outwardly to release the free end of the tongue and will simultaneously swing the free end of the tongue outwardly, and means to latch the front plate to the back.

3. In a belt buckle, a back, a tongue pivoted to the back and having a free end, a member connected to the back and engageable at its rear with the free end of the belt, and with the free end of the tongue on its front side,

a front plate hinged at one end to the back at a point adjacent to the member to hold the free end of the tongue against said member, the opposite end of the front plate being free and engageable with the free end of the belt whereby upon outward swinging of the free end of the belt same will swing the front plate

outwardly to release the free end of the tongue and will simultaneously swing the free end of the tongue outwardly, and means to 10 latch the front plate to the back.

In testimony whereof I have signed my name to this specification.

WILLIAM C. FOSTER.
